C. S. TAYLOR

JUVENILE JUMP SEAT

Filed June 1, 1925

FIG. 1

FIG. 2

FIG. 3

INVENTOR.
Charles S. Taylor.
Julien de Bried.

ATTORNEY.

UNITED STATES PATENT OFFICE.

CHARLES S. TAYLOR, OF FRESNO, CALIFORNIA.

JUVENILE JUMP SEAT.

Application filed June 1, 1925. Serial No. 34,109.

My invention relates to playthings for children and has for its principal object a novel jump seat adapted to give a child both pleasure and healthful exercise. Lesser objects are simple construction, cheapness, portability, adjustability to suit children of various weights and sizes, and withal a device of this kind which will be free from danger to small children using it.

10 I attain the objects mentioned by the jump seat construction shown in the accompanying drawings and in which:—

Figure 1 is a side elevation of the device with seat in normal position, and in dotted lines the seat is shown in lower position as though depressed by the weight of a child.

Figure 2 is a plan view looking down on Figure 1, and Figure 3 is an end view of Figure 1.

20 In further detail my jump seat construction comprises a lower skeleton frame adapted to be placed upon the floor or ground 1 and having a pair of longitudinal members 2 lying on the ground and at one end being joined to a pair of vertically arranged members 3 forming an upright. This upright is rigidly secured to the horizontal members and firmly braced thereto by angularly disposed rods 5.

30 The frame is preferably constructed of light angle bars, and the rear ends are conveniently curved as at 2' to avoid sharp corners.

The vertical members 3 diverge outwardly at their lower ends, and the horizontal members 2 lie parallel to one another in spaced relation and are tied in this arrangement by one or more cross members as shown at 6 and 7, the cross members being 40 securely riveted to the horizontal members.

The upper ends of the upright members 3 are best made continuous as indicated at 8 or otherwise secured together, and are preferably bent so as to lie parallel for a short distance near their upper ends as shown in Figure 3, and a hole is drilled through the parallel portions to support the main pivot bolt 9 of the seat supporting bar or upper frame 10.

50 The seat supporting bar or upper frame 10 extends horizontally from the upright members 3, and while it may be of any suitable material, such as hard wood, or metal, it is here shown as made of an inverted channel iron with a seat 11 transversely ar-

ranged on the outer or free end and slidably adjustable along the bar.

In front of the seat, and also slidably adjustable along the bar 10 is a pair of handles or "handle bar" 12 adapted for gripping by a child sitting on the seat and straddling the bar.

At the opposite end the upper frame or bar 10 has a downwardly extending arm 13 braced to the horizontally extending portion 65 by a pair of gusset plates 14 through which the pivot bolt 9 extends so that the bar 10 is free to oscillate at its outer end along the dotted arc 15, though it is normally forced to the high position as shown in full lines 70 in Figure 1 by a spiral spring 16 pulling on the lower end of the arm 13.

This spring 16 is preferably enclosed in a tubular working barrel or short section of pipe 17 secured to the frame cross member 75 6 by the strap 24, or otherwise.

The spring barrel 17 has a cap 18 secured to one end, and against the inner face of which the compression spring 16 reacts.

A bolt rod 19 passes loosely through a hole 80 in the cap and entirely through the spring and is provided at the end with a nut 20 and washer 21 bearing against the end of the spring so that the compression of the spring may be varied through means of a 85 socket wrench introduced into the open end of the pipe.

At the outer end the rod 19 is formed with an eye 22 and is loosely linked to the end of the arm 13 by a link 23 so that in 90 forcing the bar 10 downward as through means of a child upon the seat 11, the arm 13 will swing to the left and by pulling the link 23 and rod 19 will compress the spring against the cap 18 of the pipe. 95

The amount of spring compression is controlled by the nut 20 to just balance a rider on the seat when in lower dotted position so that the child can get a good kick upon the ground for an upward ride. The spring 100 may be further adjusted to determine the maximum rise of the bar 10 by adjusting the pipe at the desired position in the clamp 24.

The amplitude of the oscillatory movement may be reduced by sliding the seat and handles nearer to the pivotal support of the bar 10, and the handles affording a secure grip for a youngster's hands prevent the child from falling.

In fact, a year's test of one of these de- 110

5 vices, which though used with considerable violence by children, was without a single accident, thus demonstrating its entire practicability and safety.

5 In considering the invention as above specified and shown in the drawings, it will be evident that the device may be considerably modified both in frame construction 10 as well as in arrangement of the spring, yet 10 carry out the objects of the invention, and any such modifications as come within the spirit of the invention are sought to be covered in the appended claims.

I claim:

15 1. In a juvenile jump seat of the character described, a supporting frame having an upright, a horizontally disposed seat carrying arm pivoted to the upright and spaced above the supporting frame and said arm 20 having a downwardly extending portion, a spiral compression spring mounted on the frame, a tubular housing covering the spring and supporting one end thereof

against compression, and a rod connected to said downwardly extending portion of the 25 arm extending through the spring and having adjustable means thereon bearing against the opposite end of the spring for compressing the spring within said tubular housing upon downward movement of the 30 arm.

2. In a juvenile jump seat of the character described, a supporting frame having an upright, a horizontally disposed seat carrying arm pivoted to the upright and 35 spaced above the supporting frame, said arm having a downwardly projecting portion, a compression spring mounted on the frame and provided with means for retaining it in case of breakage, and means extending from the downwardly projecting portion of the arm engaging the spring for compressing the same upon downward movement of the arm.

CHARLES S. TAYLOR.
